UNITED STATES PATENT OFFICE.

ALFRED N. OLSEN, OF ROCK RAPIDS, IOWA, ASSIGNOR TO ACME SCREEN DOOR MANUFACTURING COMPANY, OF ROCK RAPIDS, IOWA, A CORPORATION.

COMBINED INSECT-TRAP AND SCREEN-FRAME.

1,248,427.

Specification of Letters Patent.

Patented Nov. 27, 1917.

Application filed August 23, 1917. Serial No. 187,867.

To all whom it may concern:

Be it known that I, ALFRED N. OLSEN, a citizen of the United States, residing at Rock Rapids, in the county of Lyon and 5 State of Iowa, have invented certain new and useful Improvements in Combined Insect-Traps and Screen-Frames, of which the following is a specification.

This invention relates to improvements in 10 combined screens and insect traps, more particularly for use in connection with screen doors, but which may be used in connection with window screens and other similar openings.

15 The principal object of the present invention is to provide a combined trap and screen which takes the place of a portion of the upper part or panel of the screen material of a screen door to prevent the entrance of 20 flies and other insects when the door is opened.

Another object of the invention is to provide a device of this character in which the insects are trapped and the device arranged 25 to be detached from the screen frame and opened to permit the destruction and removal of the trapped insects.

With these and other objects in view, the invention consists in certain novel features 30 of construction, as hereinafter shown and described and then specifically pointed out in the claims; and in the drawings illustrative of the preferred embodiment of the invention—

35 Figure 1 is an elevation from the interior of a screen door with the improved device applied;

Fig. 2 is a section enlarged on the line 2—2 of Fig. 1;

40 Fig. 3 is a view similar to Fig. 2 with the parts in open position;

Fig. 4 is an elevation from the exterior of a screen door with the improved device applied and including the door frame;

45 Fig. 5 is a plan view of the improved device engaged with the screen frame and the latter attached to the door frame, the screen frame and door frame being in section on the line 5—5 of Fig. 4.

50 The improved device may be applied either to an ordinary screen door frame or to a window screen frame, but for the purpose of illustration is shown applied to a screen door frame, but it is not desired to limit the invention to any specific form of screen

frame or to screen frames employed in any specific form of opening. In the drawings employed to illustrate the preferred embodiment of the invention the members of the screen frame are represented at 10, and the 60 door frame members at 11.

The screen frame is divided near the upper part by a transverse member 12 into a relatively small upper panel and relatively large lower panels. The lower panels are 65 covered with screen material indicated at 13.

Fitting within the panel above the transverse member 12 is a frame device formed in coacting oblong portions indicated at 14—15 hingedly united at one edge, as shown 70 at 16, and provided with a suitable catch represented at 17 at the opposite edge to hold the members 14—15 in closed position. The outer face of the frame member 15 is entirely covered with screen material, indicated at 18, while the frame 14 is covered for the major portion of its outer face with screen material represented at 19. A holding rod 20 extends between the side members 75 of the frame 14 and spaced above the lower edge of the same, while a similar rod 21 extends across the frame 15 in the same manner. When the members 14—15 are disposed in closed position as shown in Fig. 2 the rods 80 20—21 are spaced at a relatively short distance. The screen material 19 is extended inwardly and thence upwardly as shown at 85 22, and connected to the rod 20, thus forming an upwardly opening pocket or trap space indicated at 23. Extending between 90 the rod 21 and the lower member of the frame 15 at its inner face is a section of screen material represented at 24, the section 24 being spaced from a portion of the screen material 18 and forming a pocket like receptacle 25 similar to the receptacle or pocket 23. By this means a relatively contracted space, indicated at 26 is formed between the lower bent portion of the screen material 19 and the lower member of the 100 frame 14. When the frame members 14—15 are disposed in their closed position as shown in Fig. 2, the insects enter through the contracted space 26 and thence crawl upwardly over the surface of the screen section 24 and into the space between the screen sections 18—19 and above the rods 20—21. In their efforts to escape the insects light against the inner faces of the screen sections 18—19 and if they crawl 105 110

downwardly they pass into the pockets 23 and 25, and are thus "trapped." The insects will not attempt to escape by passing downwardly into the narrow space between the 5 rods 20—21.

The frames 14—15 correspond in combined width to the thickness of the members 10 of the screen frame as illustrated more particularly in Fig. 5. The frame 10 member 14 is provided with stop members 27 which overhang the adjacent edges of the members of the frame 10, and thus support the improved device within the main screen frame and prevents its displacement in one 15 direction. Suitable fastening devices such as buttons, represented at 28 are attached to the side members 10 and operate over the adjacent portions of the members of the frame 14.

20 Stop members or cleats 29 are attached to the frame 10 and project over the adjacent portions of the frame 15, and thus prevent the displacement of the device in the opposite direction. The stops 27, cleats 29 and 25 buttons 28 thus coöperate to detachably support the improved device in the frame 10.

The improved device is simple in construction, can be inexpensively manufactured of any required size and of any 30 suitable material to adapt it to door or window screen frames of any suitable size or structure.

Having thus described the invention, what is claimed as new is:

35 1. In a combined screen and insect trap, coacting frames movably united face to face, webs of screen material covering the entire outer face and a portion of the inner face of one of said coacting frames, and 40 webs of screen material covering a part of the outer face and a part of the inner face of the other of said coacting frames, the last mentioned webs of screen material being united at their lower edges and spaced from 45 the adjacent frame member.

2. In a combined screen and insect trap, coacting frames movably united face to face,

a web of screen material covering a part of the outer face of one of said frames, a web of screen material covering the entire outer 50 face of the other frame, supporting rods extending through the side members of said frames, and webs of screen material supported respectively by said rods, one of said rod supported webs being connected to the 55 adjacent frame members, and the other rod supported webs united at its free edge to the free edge of the first mentioned web and spaced from the adjacent frame member.

3. In a combined screen and insect trap, 60 coacting frames movably united face to face and adapted to be supported in a doorway opening, webs of screen material covering the entire outer face and a portion of the inner face of one of said coacting frames, 65 webs of screen material covering a part of the outer face and a part of the inner face of the other of said coacting frames, the last mentioned webs of screen material being united at their lower edges and spaced from 70 the adjacent frame member, and laterally extending stop flanges carried by one of said frames.

4. In a combined screen and insect trap, 75 a main frame adapted to be supported in a doorway opening and having a transverse member intermediate thereof, a web of screen material covering the frame at one side of said intermediate member, coacting frames movably united face to face and 80 adapted to be supported in the frame at the other side of the transverse member, webs of screen material covering the entire outer face and a portion of the inner face of one of said coacting frames, and webs of screen 85 material covering a part of the outer face and a part of the inner face of the other of said coacting frames, the last mentioned webs of screen material being united at their lower edges and spaced from the adjacent 90 frame member.

In testimony whereof I affix my signature.

ALFRED N. OLSEN. [L.S.]
